UNITED STATES PATENT OFFICE.

WILLIAM H. PRIDEMORE, OF ALICE, TEXAS.

BOLT HOLDER.

1,412,965.

Specification of Letters Patent. Patented Apr. 18, 1922.

Application filed May 3, 1921. Serial No. 466,601.

To all whom it may concern:

Be it known that I, WILLIAM H. PRIDEMORE, a citizen of the United States, residing at Alice, in the county of Jim Wells 5 and State of Texas, have invented certain new and useful Improvements in Bolt Holders; and I do hereby declare the following to be a full, clear, and exact description of the invention, such as will enable others 10 skilled in the art to which it appertains to make and use the same.

In the erection or the raising of structures utilizing bolts as the fastening means, difficulty is experienced in holding the bolt 15 while tightening or loosening the nut. If the work is such that the head of the bolt and the nut can be reached by the same workman injury frequently occurs by the slipping of the wrench or like tool. On the 20 other hand if the head and nut of the bolt are so situated that they cannot be reached by a single workman, the cost is materially increased because one workman is required to hold the bolt while another workman applies the nut. 25

The present invention provides means for holding the bolt stationary under all conditions so that both hands of the workman are free to apply the nut or assist materially 30 in the work.

Other objects and advantages will be apparent and suggest themselves as the nature of the invention is understood.

While the drawings illustrate an embodiment of the invention, it is to be understood that in adapting the same to meet different conditions and requirements, various changes in the form, proportion and minor details of construction may be resorted to 40 without departing from the nature of the invention.

Referring to the accompanying drawings forming a part of the specification,

Figure 1 is a plan view of a bolt holder 45 embodying the invention,

Figure 2 is an edge view thereof, and

Figure 3 is a sectional detail showing the same applied.

Corresponding and like parts are referred 50 to in the following description and designated in the several views of the drawings by like reference characters.

The device consists of a flat body 1, usually in the form of a plate of rectangular 55 outline. The body 1 is provided with a plurality of sockets or openings of different

sizes and disposition. As shown, the body 1 is provided with a central opening or socket 2 and with edge or marginal sockets or openings 3, whereby the range of usefulness of the device is increased. The several sockets or openings are adapted to receive the heads of the bolts to be held during the application of or the removal of the nuts cooperating therewith. The central opening or socket 2 is utilized when the bolt is so situated that the device may be conveniently applied. The marginal or edge sockets or openings 3 are utilized when the heads of the bolts are so situated in 70 close proximity to projecting parts as to preclude the application of the holder to admit of the head of the bolt entering the opening 2. Lateral projections 4 are provided on a side of the body 1 and serve 75 primarily to space said body from the work to insure proper application of the holder to the head of the bolt. Bolts are usually provided with one or more washers and the projections 4 space the holder from the work 80 to compensate for said washers and insure the heads of the bolts being properly received in the sockets or openings. Moreover, the projections 4 space the body from the work in a manner to admit of a suitable 85 pry being utilized for removing the holder in the event of it becoming necessary to utilize force for this purpose. The projections 4 are formed with openings 5 which extend through the body 1 and are adapted 90 to receive a pin or spike 6 whereby the holder is retained in proper position when applied to the bolt. The pin or spike 6 is driven into the work 7, as indicated in Figure 3, and the holder is slipped upon the 95 pin 6 and over the head of the bolt 9 and is retained in place by means of a set screw 8 threaded into the body 1 and having its inner end engaging the pin or spike 6. 100

The several bolt head receiving openings or sockets are adjustable and for this purpose reducers 10 are provided. The reducers 10 are in different sizes so that the required size may be selected and fitted to the 105 opening or socket selected to adapt the same to the size of the bolt head. In the preferred form the reducers 10 are of L-shape so as to fit adjacent sides of a socket or opening, whereby to reduce the same symmetrically with reference to the original shape of the bolt opening or socket. 110

The openings 5 formed in the body 1 may be of any form desired or found most convenient in the manufacture of the device. The article is usually formed by casting and if preferred or found most advantageous the openings 5 may be round as indicated in dotted lines at the top of Figure 1. Round openings may be bored or enlarged by reaming and in some instances may be preferred.

What is claimed is:

A bolt holder consisting of a flat body provided with intermediate and marginal sockets or openings of different relative

sizes for cooperation with the heads of different sized bolts, and having spacing projections on one side, said projections having openings therein extending through the body, and set screws having their inner ends adapted to enter the openings of the projections.

In testimony whereof I affix my signature in presence of two witnesses.

WILLIAM H. PRIDEMORE.

Witnesses:

W. K. WILLIAMSON,
HENRY FEHRENKAMP.
